PHONOGRAPH PICKUP ARM

James E. Vistain, Jr., and Samuel E. Adler,
Chicago, Ill.

Application March 9, 1949, Serial No. 1,296

Term of patent 14 years
(Cl. D26—14)

To all whom it may concern:

Be it known that James E. Vistain, Jr., and Samuel E. Adler, citizens of the United States, residing at Chicago, in the county of Cook, State of Illinois, have invented a new, original, and ornamental Design for Phonograph Pickup Arm, of which the following is a specification, reference being had to the accompanying drawing, forming part thereof.

Fig. 1 is a top plan view of a phonograph pickup arm, showing our new design;

Fig. 2 is a side elevational view of the same; and

Fig. 3 is an end elevational view of the pickup arm, the right hand end of said arm being nearest the observer.

We claim:

The ornamental design for a phonograph pickup arm, as shown.

JAMES E. VISTAIN, JR.
SAMUEL E. ADLER.
